(57) CLAIM

An ornamental design for the personal table game kiosk, as shown and described.

DESCRIPTION

FIG. 1 is front, three-dimensional, isometric view of our personal table game kiosk showing our new design. A player bumper, drink holders, and the outer edge of the personal table game kiosk are shown in dashed lines, and are not part of the claimed design;

FIG. 2 is a back, three-dimensional, isometric view of the design of FIG. 1; and,

FIG. 3 is top plan view of the design of FIG. 1.

1 Claim, 3 Drawing Sheets
